3 Claims. (Cl. 241—30)

This invention relates to apparatus and method for the control of grinding equipment such as a wet and/or dry ball mill, rod mill, tube mill, autogenous mill or the like, and more particularly to control apparatus and method which comprehends simultaneously developing several continuous signals representative of variables involved in grinding process and combining these several signals in selectable amplitude proportions in a computer-amplifier to produce control signals which can be applied as required for stable high efficiency operation to obtain a product having preselected characteristics at a preselected substantially continuous production rate.

The mill grinding of raw materials to produce useful end products such as cement and the like involves feeding one or more raw materials or ores into a ball mill, rod mill, autogenous mill or the like apparatus and wet or dry grinding the materials fed in until they are broken up and intermixed to a product having preselected particle size and surface areas in a mixture of preselected constituent ratios. If all parameters of the arrangement and conditions within the grinding equipment remain constant and stable, the quantity per unit time and quality of the product will also remain steady and stable. For short time periods stable operation usually obtains in known grinding techniques. For protracted times of continuous operation, however, conditions in the grinding circuit may vary with consequent undesirable effects on the end product. The grinding machinery is, of course, capable of performing a finite amount of work according to its design, said work comprising the overcoming of normal losses plus the grinding of the fed materials to the required surface area of product and the removal of the product. In some instances mill output is screened in a separator and oversized particles in the product are recirculated and refed into the mill for further grinding and reduction to the desired product size. If the discrete particle size of a feed material increases, more work will be attributable to the recirculation chore and the quantity and/or surface area of the end product will tend to decrease. Extraordinary increases in feed particle size will quickly overload the grinding circuit. Conversely, a decrease in feed particle size will result in a lower circulating load and a higher than specified product quality and production rate.

In the materials reduction art, known methods and apparatus for control of grinding mill equipment involve the adjustment of feed rates to the mill of one or more raw materials in accordance with power consumption of the grinding machinery drive motors and with mill noise. Power consumption is relative to the particle size and the hardness of the feed material being milled and sounds emanating from the mill vary in frequency and/or amplitude according to the size, surface area and quantity of the particles in process. In systems where some portion of first-milled product is recirculated to the mill inlet for further grinding, the power consumption in the recirculating system is relative to recirculated volume and thus to the feed ratio of new material to recirculated material. Control of mill operation can be effected in a number of ways to produce desired results. An operator of a cement mill, for example, may regulate for a constant surface area of product, with some latitude tolerated in the production output rate, by decreasing and increasing the feed rate. In addition, he may maintain the desired surface area of product at an intentionally lowered out-

2

put rate by increasing grinding time when the grindability or hardness characteristics of the feed changes. With certain types of feeding components operating at set speeds the feed rate varies with flowability of the feed, moisture content, line voltage variations in power supplies, bin cavitations or hang-ups and feeder flushing. An increase in feed rate due to a change in one of such feedability variables will result in an increased ore charge volume, increased circulating load and larger discrete particle product size with consequent reduction of total surface area per unit weight and volume in the end product. Conversely, a decreased feedability will tend to lead to mill grind-cut and the end product may be overground to a higher than specified surface area. To control operation for these occurrences, mill loading may be monitored and the feed rate controllably varied to maintain optimum grinding circuit loading and/or the product output may be monitored, by weighing for example, and the feed rate varied accordingly.

20 As far is known, all of the above-described control techniques involve a human operator at some point in the arrangement. Persons skilled in the art recognize that control dependent on a human operator is prone to subjective error, inaccuracy, insensitivity and unsatisfactory reproducibility. While many modern control systems utilize signal-producing monitoring devices such as indicating and recording wattmeters, microphones with sound amplifiers or visual indicators and the like, no completely automated and completely satisfactory system for grinding mill control has been available to industry prior to the time of the present invention.

It is, then, the primary object of the present invention to provide a fully automated apparatus arrangement and method for controlling grinding mills and equivalent equipment which, in normal operation, is completely free from subjective error attending systems involving human operators.

It is a further object of this invention to provide grinding mill control wherein signals developed through the monitoring of several different process variables are combined to produce useful continuous control signals which are applied to effect changes in desired directions of the monitored variables.

It is a still further object of the present invention to provide for combining several signals produced by monitoring process variables in selectable ratios of a signal valve or amplifier.

A still further object of the present invention is to provide novel electronic circuitry for inverting signal amplitudes to render them suitable for combination with other signals in the overall control scheme.

Another important object of the invention is to furnish a control system capable of initiating corrective and alarm actions upon the occurrence of malfunctions and extraordinary conditions.

With the foregoing and other objects in view which will become more apparent hereinafter, the invention will now be described with greater particularity and with reference to the drawing which is a schematic diagram of a control system according to our invention.

In general, the present invention comprehends monitoring separate variables in a grinding process with components capable of producing discrete signals representative of instantaneous values of said variables, adjusting the respective amplitudes and phases of signals so developed, combining the several signals additively continuously in a computer and developing in said computer a control signal which can be applied to effect changes in at least one operating parameter of the grinding system.

In the drawings, there is shown a two-compartment cement grinding mill 11 having an inlet or charging end 13 and an outlet or discharge end 15. A charging header

17 connects to the inlet 13 and manifolds to a gypsum feeder 19 and a clinker feeder 21. The mill outlet 15 connects to a discharge header 23 which in turn connects to an elevator 25. Elevator 25 empties output from the mill into a conveyor 27 which carries the particized output to a separator 29. In separator 29, the mill output is screened continuously and separated into product particles having the desired surface area characteristics and tailings or particles of larger than the preselected size. Product particles are continuously removed through a product header 31 and bagged, stored or otherwise handled. The tailings are converged through a recirculating tailings header 33 to the charging header 17, adding the tailings to the continuously supplied charges from the gypsum feeder 19 and the clinker feeder 21.

A clinker feeder speed controller 35 is operably connected to clinker feeder 21 and a gypsum feeder speed controller is similarly connected to the gypsum feeder 19. A feeder ratio controller 39 connects to the speed controllers and provides for adjustment of the feed ratio. Elevator motor 41 provides driving power for the elevator 25 and separator motor 43 provides driving power for the separator 29.

In any particular control system embodying the present invention, the first decision to be made is to select the type, location and number of sensing or monitoring devices. Persons skilled in the art will recognize the importance of this consideration and will also recognize that conventional methods of system analysis will readily provide exact design answers in applying the present invention. The type, location and number of system sensing points is governed by the complexity of the grinding circuit, the system time constants, the duty limitations of discrete components in the grinding circuit and the economics of the particular grinding operation. A grinding arrangement involving two cascaded mills with two elevators and separators may require three or more sensors. A single compartment ball mill in a simple grinding system may be made to perform quite acceptably with one sensor, probably a sound sensor. High powered multi-compartment mills may operate optimally with a sound sensor for each separate compartment. The typical two compartment closed circuit system can usually be satisfied with one sound sensor and one power sensor. However, if the second compartment tends to overload for any reason, addition of a second sound sensor may be indicated. For the purposes of this description a two compartment mill, elevator, separator, recirculation and monitoring with two sound sensors and two power sensors will be considered.

Three types of sensors useful in connection with the practice of this invention are presently commercially available scil., sound sensors, power sensors and temperature sensors. The sound sensor is essentially a microphone. Sound emanating from a grinding mill consists basically of noise generated by steep wave-front impact sounds and contains frequencies from below 100 c.p.s. to well over 100,000 c.p.s. Ambient sounds from motors, gear boxes, bearings and other machine components are predominantly in the 60 c.p.s. to 1500 c.p.s. portion of the spectrum, with peaks occurring at 60, 120 and 180 cycles, corresponding to the line frequency and its second and third harmonics. Sound sensors used in monitoring chores according to this invention are customarily provided with suitable band pass filters to reject unwanted frequencies and ensure the development of control signals representative of grinding circuit performance. Commercially available electronic watt converters are suitable for use as power sensors. The power consumed by an electric drive motor is directly related to the amount of work being performed. In connection with elevators, conveyors, separators and the like equipment in grinding systems, the power sensor provides for monitoring of grinding circuit throughout and/or circulating load. Temperature sensors in the form of resistance temperature

detectors may also be installed at points in the system where temperature variations are to be monitored towards determining work load. As noted hereinabove, the present invention will be described by considering two 5 microphones and two power sensors.

Referring to the drawing, the mill compartment adjacent inlet 13 has a first microphone 45 arranged in juxtaposition thereto. Similarly, a second microphone 47 is installed adjacent the second compartment of the mill 11. These microphones 45, 47 connect respectively 10 to electronic sound sensors and inverters 49 and 51. The power circuit to elevator motor 41 is monitored by a first electronic watt converter 53 and the separator drive motor 43 is monitored by another electronic watt converter 55.

The circuits shown schematically at 57, 59, 61, and 15 63 conduct the respective signals developed in sound sensors 49, 51 and electronic watt converters 53, 55 to input points on a computing amplifier 65. In computing amplifier 65, the several continuously received signals 20 from the sensors or monitoring devices are combined according to preselected proportions and made to develop a feeder control signal which is continuously applied to the feeder speed controllers 35, 37 through circuit 69 and the feeder ratio controller 39. In other words, the output terminals of the computing amplifier deliver a voltage or current suitable for controlling the rate of feed and the feed ratio for the grinding circuit. Computing amplifier 65 is provided with a manually adjustable system set point potentiometer 71. The computer amplifier operates so that the sum of all sensor signals is revealed to any preselected set point on potentiometer 71 and a tendency of one or more sensors to depart from the set point above or below preselected limits will cause 25 a corrective or alarm signal to be initiated. In normal operation the potentiometer 71 is readjusted only when changing product specifications. When the output voltage of the computing amplifier exceeds the voltage required to produce a maximum feed rate, the feeders are 30 not supplying sufficient feed volume to satisfy the system set points. Timing circuitry in the computer amplifier provides for the initiation of a feed deficiency alarm signal or corrective signal when the excess voltage obtains 35 for a preselected period.

The monitoring signals from the microphones and 40 electronic watt converters are produced and utilized as follows: Microphone 45 detects in accordance with sound impinging thereon changes in feed size, grindability and feed rate. Since in time and flow sequence microphone 45 is ahead of microphone 47, it will lead microphone 47 and both of the power sensors or electronic watt converters 53, 55 in signal production by some finite time. Microphone 47 produces a signal indicative of the condition of the feed charge in the second compartment of mill 11. The electronic watt converter 53 produces a 45 signal representative of the power required to elevate the product plus the circulating load. The additive effect of the signal produced by converter 53 can be adjusted according to circulating load volume. Electronic watt converter 55 produces a signal representative of power consumed by the separator motor drive. This signal can also be adjusted for varying additive effect in development of the cumulative control signal produced in the computing amplifier 65.

50 Separate sensor ratio summing controllers in computing amplifier 65 permit selection of the desired proportional bands required to produce the desired amount of corrective action from each sensor. Each component of the grinding circuit, first compartment, second compartment, elevator and separator has its own particular design overload point. Under abnormal or transient grinding conditions one or more of these components could be overloaded even though other components of the circuit were operating satisfactorily. This possibility requires that each sensor be individually capable of re- 55

ducing the feed rate if and when its signal amplitude exceeds a preset value representing overload limit. Below this point, the sensor signal will contribute its voltage to the summing network in computing amplifier 65 as a controlling signal. Above the pre-established value said sensor will effect time overriding action a reduction in the feed rate irrespective of the signal values from the other sensors. The computing amplifiers circuitry also includes a minimum feed rate adjustment, a maximum feed rate adjustment and a reset action, particularly useful in coping with the wide time lags encountered in grinding operation.

In a particular embodiment of the present invention, the computing amplifier used is a Model CA10 computing amplifier manufactured by Milltronics, Ltd., Peterborough, Canada. The electronic watt converters employed are Model WA11 watt meter amplifiers made by Milltronics, supra and the sound sensors Model SS13 of the same manufacturer.

The equipment components used and arranged in the combination according to the present invention can be seen then to provide an extraordinary flexible and precise control method and apparatus arrangement. While the essential rationale of the invention involves the continuous monitoring of several separate points in the grinding circuit and the additive combination of signal indicia representative of variables of interest in the process and combination of these to produce a useful control signal, many additional benefits are provided such as malfunction alarms and provision for overriding control signals upon the occurrence of extraordinary conditions in the process.

The present invention therefore can be seen to constitute an unusually sophisticated advance in the art. While, for the purposes of describing the present invention a specific embodiment has been treated in detail sufficient to permit practice thereof, there will undoubtedly occur to persons skilled in this art many modifications which will come within the spirit of our invention. Accordingly, this disclosure should be construed as illustrative of our invention and in no way in a limiting sense, the scope of the invention being defined by the appended claims.

What is claimed is:

1. A method for grinding mill control which method 45 comprises monitoring at least one sound variable incident to the grinding process, which sound variable is representative of a particular condition of material in process; developing a first signal representative of the instantaneous value of the sound variable monitored; monitoring 50 at least one power consumption variable, which power consumption variable is representative of a condition of the material in process; developing a second signal representative of the instantaneous value of the power varia-

ble monitored; combining said first signal and said second signal in a computer; developing in said computer a control signal proportional to and representative of the combined first and second signals and applying said control signal to effect changes in a process parameter which bears on the values of the signals monitored.

2. A method for grinding mill control which method comprises continuously monitoring sound emanating from a grinding mill; developing a first signal having amplitude proportional to and representative of the amplitude of the sound monitored; continuously monitoring power consumption of at least one driving element in the grinding mill circuit; developing a second signal having an amplitude proportional to and representative of the instantaneous value of power being monitored; adjusting the amplitude of at least one of said signals to effect a preselected amplitude ratio of said first signal to said second signal; combining said first signal and said second signal in a computer; developing a control signal having an amplitude representative of the combined value of the first signal amplitude and the second signal amplitude and applying said control signal to feeder speed control apparatus to effect changes in feed rate of raw materials being fed to the grinding mill.

3. Apparatus for the control of a grinding mill used to effect reduction in particle size of raw materials fed thereto continuously, which apparatus comprises in combination sound detector means disposed to continuously monitor sound emanating from said mill; means for converting said sound monitored to a first continuous signal having an amplitude representative of the instantaneous amplitude of the sound monitored; electric power measuring means disposed to continuously measure power consumed by at least one electric monitor drive element in the grinding mill circuit; means for developing a second signal having an amplitude representative of the power measured by said last-named means; computer means in circuit with said means for developing said first signal and means for developing said second signal, said computer means being adapted to combine said first signal and said second signal into a control signal and to apply said control signal to effect changes in the mill feed characteristics.
